ABSTRACT OF THE DISCLOSURE

The application of certain oxidation catalysts to baked-on fat deposits on oven surfaces reduces temperature of complete decomposition. Oven cleaning compositions containing metal acetylacetones, hopcalite catalysts, sodium carbonate, cobalto-cobaltic oxide, manganese dioxide, platinum metals and compounds of platinum metals, alone and in combination with surface active agents, penetrants and catalyst promoters such as free alkali, are described.

This application is a continuation of Ser. No. 619,574, filed Mar. 1, 1967, now abandoned.

This invention relates to a method of cleaning surfaces having a tightly-adhering film of baked-on fats and greases, and to a product for assisting in carrying out this method. More particularly, the invention relates to an oven cleaner and to a method of cleaning ovens.

One of the most disagreeable tasks facing the housewife is the periodic cleaning of the oven of her kitchen stove. Ovens accumulate baked-on deposits of various food origin which adhere tightly to the enamel surfaces of the oven. The deposits are organic carbonaceous materials, and most usually result from the spattering of fats and oils from foodstuffs during cooking thereof. Proteins and carbohydrates may also contribute, but usually to a lesser extent. These deposits form a lacquer-like coating which is extremely difficult to remove with ordinary soap and water.

One current solution to this problem is an oven which is built with sufficient insulation and the appropriate equipment to operate at a temperature of about 800° F. Under this extreme temperature, the baked-on residues are rapidly oxidized and vaporized, leaving only a residue of fine ash.

The other current approach to the problem involves the use of an oven cleaner which is applied by the housewife and which is formulated to dissolve the deposit, or at least soften it so that it can be wiped away.

The cleaner may be one of two general types. One type, which is marketed variously as a jelly, a paste or an aerosol composition, relies heavily upon free alkali as its active ingredient. The second basic type of oven cleaner relies upon methyl chloride or some similar solvent and the compositions may include bodying agents or agents designed to lift the baked-on fat layer away from the surface of the oven.

The oven cleaners based on strong alkali are generally successful in that they will clean the surface of the oven if used properly. It is well known, however, that their use is extremely messy and is hazardous to the extent that severe burns may result if the cleaner comes in contact with the skin of the user. The solvent-based cleaners, on the other hand, are effective only for fat which has not yet burned onto the surface of the oven. Once the latter has occurred, the solvent-based cleaner is ineffective.

We have now found that the baked-on deposit on the oven surface may be removed by heating to temperatures significantly below those temperatures used for present-

2

day high temperature ovens, i.e., significantly below 800° F., by applying to the baked-on residue an oxidation catalyst which has the effect of reducing the temperature at which oxidation of the surface film occurs. According to our invention we have provided a substance which can be applied to an oven surface to cause baked-on fat residues to more rapidly oxidize and vaporize at a temperature near the maximum operating temperature of present-day conventional ovens, i.e., 450°–520° F. The catalyst system will lower the temperature at which cleaning occurs from 800° F. down to temperatures below 600° F. and in some cases, as low as 400° F. to 450° F.

Studies of air oxidation of the glazed fat deposits found in dirty ovens, in the absence of a catalyst, have demonstrated that complete removal of the residue by oxidation of the substances follows a temperature-time relationship. At 500° C. (932° F.), complete oxidation of baked-on fat deposits to a bare steel surface will take place in 15–20 minutes. Reducing the temperature to 450° C. (842° F.) requires from 25–30 minutes of heating to achieve the same complete oxidation, and at 425° C. (797° F.) complete oxidation occurs in approximately 45 minutes. At 400° C. (752° F.) complete oxidation requires one hour and 45 minutes, and at 350° C. (662° F.) complete oxidation requires about 6 hours.

At temperatures below 350° C. little practical oven cleaning benefit is obtained. At 300° C. (572° F.) there is little visible effect after 6 hours, and at 200° C. (392° F.) there is negligible visible effect after 43 hours.

30 The oxidation catalysts found useful according to this invention include certain metal derivatives of 2,4-pentandione, also called metal acetylacetones. The cobalt, vanadyl and manganese salts are particularly useful. Examples are $(CH_3COCHCOCH_3)_2Co$,

$(CH_3COCHCOCH_3)_3Co$

$(CH_3COCHCOCH_3)_2Mn$, $(CH_3COCHCOCH_3)_3Mn$, and $(CH_3COCHCOCH_3)_2VO$.

40 Other oxidation catalysts found useful according to the invention include those known as hopcalite type catalysts, in modified form. One such catalyst, prepared as described in Kearby in "Preparation and Development of Catalysts," Standard Oil Development Co., Linden, N.J.—Report No. CD-3P-51, has an approximate composition of 50% MnO_3 , 30% CuO , 15% Co_2O_3 , 5% Ag_2O . Each compound is separately prepared by precipitation in a water solution, then brought into slurry and mixed. The Ag_2O is precipitated onto the slurry of the first three. The sample is then washed three times, dried in an oven at 140° C. and powdered.

45 Another group of catalysts which is useful according to this invention are the platinum metals, including platinum, ruthenium, rhodium and palladium. Catalytically active compounds of these metals may be used, such as the oxides, cerates, manganates or manganites, chromates or chromites, and vanadates.

50 Other suitable catalysts include Na_2CO_3 , CO_3O_4 (cobalto-cobaltic oxide) and MnO_2 .

55 Thus, the catalysts suitable for use according to this invention are those from the group consisting of the metal acetylacetones, hopcalite catalysts, sodium carbonate, cobalto-cobaltic oxide, manganese dioxide, platinum metals and compounds of platinum metals.

60 These catalysts are useful by themselves or with diluents, such as carbon. Each of these materials can also be used in various admixtures with each other to provide various desired effects. Coloring materials may be employed, and various masking agents may be used to avoid unwanted colors.

65 In certain cases, it has been advantageous to employ small amounts of catalyst promoters with the catalyst

described above. Particularly good results have been obtained with the catalysts modified with potassium hydroxide and sodium carbonate as alkaline promoters. Sucrose and manganese dioxide have also been useful in this capacity. Generally speaking, a level of about 1% of promoter based upon the weight of the catalyst has been used to advantage.

The catalyst described above may also be advantageously supported on carriers such as chromia and alumina. Methods for obtaining chromia type catalysts are described in the article by Feighan and Davis, Journal of Catalysis, vol. 4, p. 594, 1965. Preparation of this type catalyst is accomplished by depositing a catalytically active substance, such as a metal acetylacetone, on the base ceramic material in accordance with procedures known in the art.

The catalyst of the present invention is most conveniently applied to oven surfaces as a paste or gel containing a uniform suspension of catalyst, catalyst promoter and other desired ingredients, including surfactant, thickener, oxygen donor and extender. Triton X-100 is a suitable surfactant and penetrant, and may be used at a level up to about 0.5%. A level of 0.1% is preferred. Triton X-100 is an alkyl aryl polyether alcohol, i.e., acetylphenol condensed with 10 moles of ethylene oxide. Sugar-based surfactants, such as certain sucrose derivatives, as well as polyoxyethylated compounds, may also be used. Suitable thickeners include carboxymethyl cellulose, methyl cellulose, and Polyox, a trade name for a water-soluble, highly polymerized ethylene oxide. A suitable oxygen donor is KNO_3 preferably at a level of 0.5%. Suitable extenders include sodium aluminate and sodium silicate— Al_2O_3 , preferably at a 0.5% level. Other additives, promoters, color pigments and the like may be used. Suitable thickeners include carboxymethyl level. The balance of the composition is liquid and preferably is water.

The following examples further illustrate the process of this invention.

EXAMPLE I

The effectiveness of various oxidation catalysts in removing baked-on fat deposits was assessed using the procedure described below. Stainless steel plates, 1" x 4" in size and approximately $\frac{1}{82}$ " thick, were highly polished to present a nonporous surface. These plates were coated with layers of animal fats by brushing the fat onto the surface. The plate was then heated to cause partial decomposition of the fat, and successive layers were deposited. The deposited material was then heated in a Fisher burner in an open flame at temperatures approaching 800° C. until a hard glazed coating of dark brown to black coloration was obtained, similar to carbonized fatty solids found in ovens. Approximately 2-4 mg. of fat were deposited per square centimeter of plate surface.

Powdered catalyst was applied to about 40% of the total plate surface, the balance of the plate acting as a control. To assure an even coating of catalyst, the fat deposit was first moistened with a thin film of alcohol. The dry catalyst was then rubbed or spread on the fat deposit. The solvent aided the dispersion process and on drying gave a relatively even catalyst deposit. Where catalysts activators, such as sodium hydroxide and sodium carbonate, were used the activators were dissolved in the alcohol as a 1% solution and applied directly to the fat deposit.

The stainless steel plates with the fat deposit and catalyst thereon were then heated for specified lengths of time at specified temperatures. On completion of the heat treatment, the activity of each catalyst was evaluated in accordance with the following visual rating system:

A—no effect noticeable—fat deposit still glazed.

B—barely detectable effect on fat deposit.

C—intermediate effect on fat deposit, surface disrupted. 75

D—strong effect, some small amount of steel surface visible.

E—surface metal easily observable, large portions of surface cleaned.

5 Table 1 below summarizes the results obtained.

TABLE 1

Catalyst	Catalyst promoter	Temp., °C.	Time (hrs.)	Rating
10	Na ₂ CO ₃	400	$\frac{1}{6}$	C

EXAMPLE II

40 A series of oxidation catalysts were prepared and evaluated as agents for removing baked-on fat deposits. For this series, a number of stainless steel sample pans approximately 1" in diameter, and having a $\frac{1}{16}$ " lip were cleaned in hot potassium hydroxide solution, rinsed well and then air dried. The interior surface of these pans were then coated with animal and vegetable fat. The greased pans were heated at 350° C. for approximately 30 minutes in a tube furnace with free access of air to form a hard glazed deposit of fat having up to about 60 mg. per square centimeter.

45 A dry, powdered catalyst was added to each pan, and slurred in the pan with a few drops of methyl alcohol to obtain a coating of uniform thickness over the fat deposit. The deposit was then air dried for several hours to remove the solvent. Duplicates of each sample were then heated for two hours, one at 232° C. and the other at 288° C. and the weight loss occasioned by volatilization by the fat deposit was determined. Table 2 below summarizes the results obtained in these tests.

50 TABLE 2

Catalyst	Promoter	Percent by weight of fat lost by volatilization	
		288° C.	232° C.
65 CO(a.a.)	Sucrose-KOH	6.8	52.0
		82.0	4.1
Na ₂ CO ₃			18.18
CO ₂ O ₃		44.6	43.0
CO(a.a.)	Na ₂ CO ₃	16.9	11.3
CO(a.a.)	Na ₂ CO ₃	20.6	14.8
VO(a.a.)	Na ₂ CO ₃	2.2	36.8
VO(a.a.)	Na ₂ CO ₃	10.0

75 Pt-C	MnO ₂	12.3	0.2
		6.2	22.5

5

EXAMPLE III

A suitable composition for use as an oven cleaning composition according to this invention has the following formula:

Ingredient:	Percent by weight
Triton X-100	0.1
Methyl cellulose	0.5
KNO ₃	0.5
Sodium Aluminate	0.5
Catalyst (from Table 1 above)	0.5
Misc.; color pigments	0.1
Water, balance	

The composition is prepared by mixing the ingredients to form a paste. The paste is used by applying it to the surface of an oven having backed-on fat deposits and operating the oven at its maximum temperature from two to three hours.

We claim:

1. A method of removing a deposit of baked-on fats from oven surfaces comprising the steps of (1) applying to the deposit an oxidation catalyst selected from the group consisting of the cobalt, manganese and vanadyl acetylacetones and sodium carbonate, and (2) heating the deposit for a time and at a temperature sufficient to cause 25 complete oxidation of the deposit.

2. The method of claim 1, wherein the catalyst is applied to the baked-on fat deposits of an oven as a uniform suspension of powdered catalyst in water.

3. The method of claim 2 wherein the suspension of catalyst in water additionally contains a catalyst promoter selected from the group consisting of potassium hydroxide, sodium carbonate, sucrose, and manganese dioxide, at level of about 1%, based on the weight of the catalyst.

4. An oven cleaner consisting essentially of an oxidation catalyst selected from the group consisting of the cobalt, 35

6
manganese and vanadyl acetylacetones and sodium carbonate, which will catalyze the oxidative deterioration of baked-on fat deposits at a temperature below about 600° F. within a three hour period of time.

5. The oven cleaner of claim 4, wherein the composition additionally contains a nonionic surface active agent and a catalyst promoter selected from the group consisting of potassium hydroxide, sodium carbonate, sucrose, and manganese dioxide, at a level of about 1% based on the weight of the catalyst.

10 6. An oven cleaner adapted for use in oven cleaning processes conducted at a temperature below 600° F. within a one hour period of time consisting essentially of cobaltous acetylacetone as an oxidative catalyst and about 1% by weight of the catalyst of potassium hydroxide.

15 7. An oven cleaner in the form of a paste adapted for use in oven cleaning processes consisting essentially of 0.1% of an alkyl aryl polyether alcohol as a penetrant, 0.5% methyl cellulose as a thickener, 0.5% catalyst of cobaltous acetylacetone with about 1% by weight of the catalyst of sucrose and potassium hydroxide, 0.1% miscellaneous color pigments and a balance of water.
